(57) **CLAIM**

The ornamental design for a cigar cutter, as shown and described.

DESCRIPTION

FIG. 1 is a front operational view of a cigar cutter showing my new design;

FIG. 2 is an isometric view thereof;

FIG. 3 is a front elevational view thereof;

FIG. 4 a rear elevational view thereof;

FIG. 5 is a right elevational view thereof;

FIG. 6 is a left side elevational view thereof;

FIG. 7 is a top plan view thereof;

FIG. 8 is a bottom plan view thereof showing my design; and,

FIG. 9 is an isometric view of the cigar cutter in an open configuration.

The broken lines in FIG. 1 illustrate environmental subject matter only and form no part of the claimed design; All other broken lines in drawings depict portions of the cigar cutter that form no part of the claimed design.
